UNITED STATES PATENT OFFICE.

ALBERT L. FULLERTON, OF BOSTON, MASSACHUSETTS.

ROTARY PUMP AND THE LIKE.

Application filed November 12, 1927. Serial No. 232,812.

The invention has relation to organizations of the class of which the well-known gear pumps are typical, such organizations being employed usually as rotary pumps but also to some extent as rotary motors.

The invention has for its main object the production of an improved organization of the class aforesaid, embodying improvements producing an improved pump or motor and securing certain desirable results in operation. One of the special objects is to provide for securing, in the case of a rotary pump, a high rate of flow, and continuity and uniformity in the load upon the rotor shafts, with a minimum of vibration. Another is to secure a surface-seal effect which shall reduce and practically eliminate leakage from the discharge side of the rotors back to the suction or inlet side of the latter. Another of the said special objects is to eliminate water-hammer in the case of a rotary pump. Other objects are indicated in the course of the following portions of this specification.

An illustrative embodiment of the features of the invention is shown in the accompanying drawings, in which,—

Fig. 1 is a central vertical section of my improved pump, made in the plane of the driving shafts, the latter being in elevation, however.

Fig. 2 is a view in vertical section on line 2, 2, of Fig. 1.

Fig. 3 is an end elevation of the cylinder alone, and Fig. 4 is a vertical section on line 4, 4, of Fig. 3.

Fig. 5 is a side elevation, and Fig. 6 an end elevation, of one of the rotors.

Figs. 7 and 8 are, respectively, a side elevation of one of the heads which close the ends of the cylinder, and an edge view thereof partly in vertical section.

Figs. 9, 10, and 11 are side, edge and top views, respectively, of the casting for the partition by which the interior of the pump is divided into two chambers, such partition being shown in these views in one piece, as is the case prior to the casting being broken into sections to permit the assembling of the general organization.

Fig. 12 is a view in section on line 12, 12, of Fig. 4, showing one of the equilibrizing ducts by which water-hammer is obviated.

The general organization shown in the drawings includes a casing-body 1 constituting a so-called cylinder, shown as a part

of the general organization in Figs. 1 and 2 and separately in Figs. 3 and 4, it having an internal chamber within which the rotors are located, and being provided with suction and discharge ports 21 and 22, respectively, which lead to and from, respectively, the said chamber. Heads 2, 2, shown in place in the general organization in Fig. 1 and one thereof shown separately in Figs. 7 and 8, are secured to the opposite ends of the casing-body or cylinder. A cover-plate 3, Fig. 1, is secured to the outer side of one of the said heads, and a gear-casing 4 is secured to the outer side of the other head. The said organization includes also the two rotors which are shown in place in Figs. 1 and 2, and which are described later herein. In connection with the heads 2, 2, bearings are provided for the shafts 5 and 6 (Figs. 1 and 2) of the two rotors, such shafts being parallel with each other. End-portions of the said shafts project beyond one of the heads 2, 2, and have fixed thereon pinions 18, 19, Fig. 1, which intermesh with each other so as to provide for the transmission of motion from one rotor-shaft to the other to cause the two rotor-shafts and the rotors to rotate in unison. Pinions 18, 19, are enclosed by gear-casing 4. The opposite end-portion of shaft 6, extends through a hole in cover-plate 3 and a stuffing-box 31, and projects beyond the latter.

Fig. 1 shows roller-bearings 7, 7, applied to the respective heads 2, 2, and occupied by opposite portions of the two rotor-shafts. Some other form of bearing may be substituted therefor if preferred. At 8, 8, Figs. 1 and 2, are non-rotating hubs in conjunction with the heads 2, 2, such hubs constituted in this instance by bushings or sleeves which are fixed in the heads 2, 2. The rotor-shafts 5 and 6 extend through these hubs, as shown, and the respective hubs extend lengthwise of the said shafts from the respective heads 2, 2, along each of the respective shafts to near the middle of the length of the casing-body or cylinder 1. In this instance the hubs are fitted to the rotor-shafts so as to serve as plain shaft-bearings, supplementing the roller-bearings 7, 7, and sustaining the shafts and the rotors at the places where the tendency to deflection of the shafts is greatest. If desired, the roller-bearings or the preferred substitute therefor may be omitted, and the hubs 8, 8, alone may be depended upon as shaft-bearings, or, on the other

hand, the hubs may be of sufficient internal diameter to clear the shafts and the roller-bearings or the substitute therefor, alone, may constitute the shaft-bearings. Apart 5 from subserving the function of shaft-bearings, the non-rotating hubs 8, 8, have an important function in connection with the rotors and their impellers, as explained hereinafter. When the organization is employed 10 as a pump, driving power is communicated to shaft 6 through the agency of suitable appliances, not shown, connecting with the outwardly projecting portion thereof. When the organization is used as a motor, 15 the power will be transmitted from shaft 6 through connections suitable for the purpose.

Upon each rotor-shaft is mounted a rotor. The drawings show in Figs. 1, 2, 5, 6, the 20 preferred form of rotor. In this instance, each rotor is constructed at mid-length thereof with a hub 10 having a central hole or eye 11, Fig. 5, which fits the corresponding shaft, the said hub, in the assembled organization, being located upon the shaft at an intermediate point between the two cylinder-heads 2, 2, and a key 12, Fig. 1, which engages with the hub internally of the latter serving to provide for compelling rotation 25 of the rotor with the shaft. In this instance, in accordance with one portion of the invention, each rotor is provided with two sets of wings or impellers 13, 13, 14, 14, two of which (13, 13) spaced apart angularly 180°, 30 as usual, extend from the hub of the rotor toward one of the cylinder-heads 2, 2, while the other two thereof, (14, 14) similarly spaced apart angularly, extend from the hub in the opposite direction toward the opposite cylinder-head 2. The cylinder is 35 divided interiorly into two lateral chambers by means of an intermediately located partition 16, which may be of figure-8 shape, as in Fig. 9, each aperture of which is occupied 40 by the hub 10 of one rotor, so that the impellers extending in one direction at one side of the said partition occupy one of the said lateral chambers within the cylinder, while the impellers extending in the opposite direction at the opposite side of the partition 45 occupy the other lateral chamber within the cylinder. This provides two separate pumping units within the cylinder-casing. The two lateral chambers are both in communication 50 with the suction port 21 and also are both in communication with the discharge port 22. It will be perceived that the two sets of wings or impellers 13, 13, and 14, 14, of each rotor are in staggered relationship, 55 the set extending in one direction within one lateral chamber being displaced angularly 90° with relation to the set extending in the opposite direction within the other lateral chamber, so that the respective wings or impellers of one set work out of phase with 60

those of the other set, i. e., alternate in action therewith, and thereby a continuous action in pumping, &c., is secured.

In effect, the organization, as described thus far, provides a duplex structure resembling two pumps located side by side, each having its impeller wings or segments 13, 13, or 14, 14, as the case may be, disposed at an angular distance of 90° around from those of the other, and hence running 70 out of phase with one another so as to give a balanced action at all speeds, with the loads equal and shared between both shafts alike. The same load conditions are manifest in the case of both the upper shaft 5 and the lower 80 shaft 6. Each of such shafts takes 50% of the load continuously. Hence the improved organization is adapted to run at high speed with a minimum of vibration.

In practice, the partition 16 is produced 85 through being cast in one integral piece, as shown in Figs. 9, 10, 11, and machined while in that state. It is formed with weakened places in its top, middle, and bottom portions, for example by making holes 17, 17, 17, in such portions, and preparatory to assembling it with other parts in the general organization its front and rear halves are broken apart at these places. Or it might be cut through at the latter. The two 90 symmetrical halves, after being separated from each other, may be fitted readily into place around the exteriors of the hubs of the two rotors in the process of assembling the parts of the organization.

The wall of the cylinder-chamber is shaped to provide oppositely-located semi-circular interior concavities within which the rotors rotate, the interior surfaces of the corresponding portions of the said wall being concentric, respectively, with the respective shafts 5 and 6, and with the hubs 8, 8. The wings or impellers of the rotors travel around within these concavities, between the convex exteriors of the sleeves and the concave portions of the interior cylinder-wall.

In accordance with one portion of the invention, the wings or impellers of the rotors are sector-shaped in cross-section, i. e., segmental, each thereof being formed with a 105 concave inner side which fits the periphery of the hub 8 around which it rotates, and with a convex outer side which fits the concave surface of the adjacent concentric concave portion of the cylinder-wall.

It will be perceived on reference to Fig. 2 of the drawings that I provide for a considerable width, circumferentially, of sliding surface contact between the concave inner surface of a sector-shaped wing or impeller and the periphery of the corresponding hub 8, and also between the convex outer surface of a wing or impeller and the adjacent concave portion of the cylinder-wall. This sliding surface contact provides effec- 120 125 130

tually against leakage of fluid under pressure from the discharge side of a rotor to the suction side thereof.

With the same end in view, each hub 8 is formed with a peripheral concavity 15, Fig. 2, extending lengthwise of the hub and concentric with the other rotor-shaft, and the peripheries of the wings or impellers of the rotor carried by the latter shaft successively enter this concavity and make sliding contact with the concave surface of the hub as the rotor rotates. This concavity provides for such an extent of surface contact, as contradistinguished from line-contact, between the convex outer surface of an impeller and the concave surface of the opposing hub, as the impeller passes around, that leakage of fluid between an impeller and the hub, from the discharge side of the rotors to the suction side, is reduced to a much smaller amount than if there were merely a line-contact between an impeller periphery and an opposing hub surface.

Heretofore, with pumps on the order of that shown herein the working speed has been restricted, and the rate of discharge has been kept below the theoretical maximum, because of the excessive development of water-hammer when a pump of such class is driven beyond a certain critical speed varying in different types. The said water-hammer produces noise, vibration, and strain which occasionally breaks the joints of the piping with which the pump is associated. To keep down this action, the speed of the pump has had to be kept down. Such action in the case of pumps turning at high speed is due to the creation of a partial vacuum in each of the advancing pumping pockets enclosed between wings or impellers, because of the pocket having been closed by the coacting advancing wings or impellers before becoming entirely filled with fluid. When the pocket is opened suddenly to the discharge port the high pressure of the fluid occupying such port creates back-flow into the pocket, with a noticeable shock. To avoid water-hammer and render it practicable to run a pump at high speed, I provide as another feature of invention pressure-equilibrizing ducts 20, 20, Figs. 2, 3, 4, in the inner surface of the wall of the cylinder, in working relation with the rotor-wings or impellers and the pockets intervening between them. There are four of the said pressure-equilibrizing ducts shown in Fig. 4, namely two upper ones for securing the desired pressure-equalizing action in connection with the pockets at right and left, respectively, of the hub of the upper rotor in the drawings, and two lower ones for securing such action in connection with the corresponding pockets of the lower rotor. These ducts are formed in this instance, as shown by Figs.

2, 3, 4, and 12, partly in the concave portions of the inner surface of the cylinder-wall and partly in the straight portions of said wall alongside the discharge port. In the operation of the pump, the portion of a duct which extends into a concave portion of the wall is closed by the convex peripheral portion of an advancing wing or impeller, so that the advancing pocket in the rear of such wing or impeller is sealed against backflow from the discharge-chamber until the heel of such wing or impeller passes the beginning of the groove in the concave portion of the cylinder-wall. Thereupon leakage or backflow of fluid takes place from the discharge port, and through the equilibrizing duct into the succeeding pocket, until such pocket is completely occupied with fluid and the vacuum previously existing therein is filled. This avoids the action known as water-hammer, and through eliminating the disadvantageous incidents thereof enables the pump to be operated at a higher rate of speed than found practicable heretofore.

The rotors being symmetrical, the organization may be run in either direction as a pump, if desired, and by supplying fluid under pressure at one or the other port may also be run in either direction as a motor. To fit it for being run as a pump in a direction the reverse of that indicated in the drawings, equilibrizing ducts should be made at each side of the rotors, instead of at one side only thereof as in the drawings.

Fluid-pressure within the cylinder, due to the action of the rotors or otherwise resulting, may have the effect of inducing leakage of fluid between the peripheries of rotor-shafts 5, 6, and the interior surfaces of the hubs or sleeves 8, 8, lengthwise of said shafts, in opposite directions from the inner ends of the said hubs or sleeves toward the said bearings. In order that non-lubricating fluid thus leaking along the shafts may be prevented from reaching the bearings, I provide means for intercepting such fluid and conducting it to the suction-chamber. In the present instance the intercepting and conducting means comprises peripheral grooves 51, 52, 53, and 61, 62, 63, formed in the respective shafts 5, 6, extending around the latter, and holes 81, 81, in the hubs or sleeves 8, 8, extending radially within the latter from their central openings to their peripheries, such holes opening into the chamber of the cylinder at the suction side of the rotors. Grooves and holes such as just mentioned are located intermediate the inner ends of the hubs or sleeves 8, 8, and the cylinder-heads, so that the means for intercepting and conducting to the suction-chamber is entirely internal of the cylinder-casing.

The grooves are shown herein in groups of three, there being one such group for each hub or sleeve, the innermost groove 51 or 61 of each group being separated somewhat from the remaining two, 52, 53, or 62, 63, which are closer together, constituting a pair. The neighboring hole 81 in the adjacent hub or sleeve registers with the said pair. As will be apparent, fluid passing outwardly along a rotor-shaft from the inner end of a hub or sleeve will collect or accumulate within the single groove, 51 or 61, from which it will work further outward along the shaft until it enters one or both of the pair of grooves, from which it will be withdrawn by suction into the suction-chamber, thus keeping it away from bearings 7, 7.

What is claimed as the invention is:—

20 1. An organization for the purposes described, comprising, essentially, a cylinder-casing having opposite concave portions of cylindrical curvature, non-rotating cylindrical hubs in pairs, those of each pair concentric with the adjacent concave portion of the cylinder-casing extending toward each other from opposite ends of the cylinder-casing and spaced apart at their proximate ends, rotor-shafts within said pairs of hubs, and impeller-hubs mounted on said rotor-shafts, projecting radially outward between said proximate ends, and provided with impellers extending axially of the rotor-shafts in opposite directions, with the impellers of the respective rotor-shafts intermeshing in their rotation, and with the intermeshing sets that extend in one direction displaced angularly with relation to those extending in the opposite direction 40 so as to produce alternating action whereby continuity and uniformity in the load upon the two rotor-shafts is maintained.

2. An organization for the purposes described, comprising, essentially, a cylinder-casing, a rotor-shaft extending transversely with relation to the said cylinder-casing, a rotor carried by said rotor-shaft and working within said cylinder-casing, a shaft-bearing in connection with said cylinder-casing, and a sleeve-like hub extending from said cylinder-casing longitudinally of the rotor-shaft and having means internal of the cylinder-casing for intercepting non-lubricating fluid passing along the rotor-shaft before such fluid reaches the bearing.

3. An organization for the purposes described, comprising, essentially, a cylinder-casing, a rotor-shaft extending transversely with relation to the said cylinder-casing, a rotor carried by said rotor-shaft and working within said cylinder-casing, a shaft-bearing in connection with said cylinder-casing, and a sleeve-like hub extending from said cylinder-casing longitudinally of the rotor-shaft and having means internal of

the cylinder-casing for intercepting non-lubricating fluid passing along the rotor-shaft before such fluid reaches the bearing, comprising a fluid-intercepting groove in the rotor-shaft extending around the latter and a hole in the said hub registering with such groove and opening into the suction-chamber of the pump.

4. An organization of gear-pump type comprising, in combination, a casing, a rotor therein having two sets of impeller members joined by an intermediate cylindrical hub, the said sets extending in opposite directions from said hub and each other, and a partition fitting about the hub and dividing the casing into two lateral chambers, each of which is occupied by one of said sets of impeller members.

5. An organization of gear-pump type comprising, in combination, a casing, paired rotors therein each having sets of impeller members joined by an intermediate cylindrical hub, and extending in opposite directions from said hub and each other, and a partition fitting about the respective hubs and dividing the casing into two lateral chambers, each of which is occupied by paired sets of impeller members.

6. An organization of gear-pump type comprising, in combination, a casing, a rotor therein having at each end a pair of impeller members, joined by a cylindrical hub between the two pairs, the said pairs extending in opposite directions from the said hub and each other, and a partition fitting about the said hub dividing the casing into two chambers, through each of which fluid flows, the members of each pair being angularly displaced with respect to the members of the other pair to work out of phase with such other pair.

7. An organization of gear-pump type comprising, in combination, paired rotors therein each comprising an intermediate hub and pairs of impeller members extending in opposite directions from the said hub, and a partition fitting about the two hubs and dividing the casing into two chambers, through each of which fluid flows, with the members of the pairs which extend in one direction angularly displaced with respect to those of the pairs which extend in the opposite direction so as to work out of phase with the latter pairs.

8. In an organization of gear-pump type, the combination with a cylinder having a rotor-compartment divided by a partition into lateral chambers, and a pair of rotor-shafts, of cylindrical members surrounding each of the respective shafts and extending from opposite ends of the cylinder toward the said partition, and a pair of rotors comprising intermediately-located hubs by which the respective rotors are engaged with the respective rotor-shafts, said hubs

occupying holes in the partition, and impellers which extend in opposite directions from each of the said hubs and the partition and in the rotation of the rotors revolve around the said cylindrical members in sliding contact with the peripheral surfaces of the latter.

9. In an organization of gear-pump type, the combination with a cylinder having 10 rotor-compartments separated by an intervening partition, and a pair of rotor-shafts, of bushings extending from the ends of the cylinder toward the said partition and fitting the rotor-shafts, and a pair of rotors comprising intermediately-located hubs by 15 which the respective rotors are mounted upon and engaged with the respective rotor-shafts, and impellers which extend in opposite directions from said hubs and the said 20 partition and revolve in sliding contact with the peripheries of the said bushings.

10. An organization of gear-pump type comprising, in combination, a casing, a rotor 25 therein having alternate impeller members and pockets for fluid, and a pressure-equalizing inlet adapted to permit access of the fluid at the discharge side into the advancing pumping pocket before the said pocket is opened at the discharge port.

30 11. An organization of gear-pump type comprising the combination with a casing, and paired rotors therein having a plurality of impelling members thereon, of a pres-

sure-equalizing duct adapted to give access 35 of the fluid at the discharging side of the pump into the advancing pumping pocket before the said pocket is opened at the discharging point.

12. A gear-pump comprising in combination a casing, and paired rotors therein 40 provided with a plurality of fluid-impelling members with intervening pockets for fluid, and having means to admit gradually 45 the fluid standing at the discharging side of the pump into a pocket between fluid-impelling members before such pocket is discharged.

13. A gear-pump comprising in combination a casing, and paired rotors therein 50 provided with a plurality of fluid-impelling members and intervening pockets for fluid, and having means to bring the fluid pressure within a pumping pocket between impeller members gradually to the same pressure as that of the fluid at the discharging 55 side of the pump.

14. A gear-pump comprising the combination with a casing, and paired rotors 60 therein provided with a plurality of fluid-impelling members, of means to bring the fluid pressure within a pumping pocket between such impelling members gradually to the same pressure as that of the fluid at the discharging side of the pump, before said pocket is opened at the discharging point.

ALBERT L. FULLERTON.
